US00D771107S

(12) **United States Design Patent** (10) **Patent No.:** **US D771,107 S**
(45) **Date of Patent:** **** Nov. 8, 2016**

(54) **DISPLAY SCREEN WITH GRAPHICAL USER INTERFACE**

(71) Applicant: **TeleTracking Technologies, Inc.**,
Pittsburgh, PA (US)

(72) Inventor: **Jason A. Spector**, Pittsburgh, PA (US)

(73) Assignee: **TELETRACKING TECHNOLOGIES, INC.**, Pittsburgh,
PA (US)

(**) Term: **15 Years**

(21) Appl. No.: **29/537,874**

(22) Filed: **Aug. 28, 2015**

(51) LOC (10) Cl. **14-04**

(52) U.S. Cl.

USPC **D14/486**

(58) **Field of Classification Search**

USPC D14/485-495

CPC G06F 17/212; G06F 17/246; G06F
17/3005; G06F 17/30112; G06F 17/30716

See application file for complete search history.

(57) **CLAIM**

The ornamental design for a display screen with graphical user interface, as shown and described.

DESCRIPTION

The patent or application file contains at least one photograph executed in color. Copies of this patent or patent application publication with color photographs(s) will be provided by the Office upon request and payment of the necessary fee.

The FIGURE is a front view a display screen with graphical user interface showing my new design.

The broken lines of uneven length show the display screen. The broken lines form no part of the claimed design.
